UNITED STATES PATENT OFFICE.

MARK P. BRENNAN, OF NEW YORK, N. Y.

MUCILAGE-BOTTLE.

SPECIFICATION forming part of Letters Patent No. 604,245, dated May 17, 1898.

Application filed September 3, 1897. Serial No. 650,520. (No model.)

To all whom it may concern:

Be it known that I, MARK P. BRENNAN, a citizen of the United States, residing at New York, in the county of New York and State 5 of New York, have invented certain new and useful Improvements in Mucilage-Bottles, of which the following is a full and complete specification, such as will enable those skilled in the art to which it appertains to make and 10 use the same.

This invention relates to attachments for mucilage-bottles, and more particularly to that class thereof which are designed to keep the neck of the bottle free from gum.

15 The object of the invention is to provide an attachment of the above-described class which can be placed within the neck of the ordinary mucilage-bottle and which will present such surfaces as will prevent the brush under any 20 circumstances from coming in contact with the inner periphery of the neck of the bottle, unless it is designed that it so should.

25 A further object is to provide an attachment that is simple in construction, that can be readily placed within the bottle, and that will be comparatively inexpensive to manufacture.

30 The invention consists in the novel features of construction hereinafter set forth and described, and more particularly pointed out in the claims hereto appended.

35 Referring to the accompanying drawings, which form a part of this specification, Figure 1 is a sectional elevation of a mucilage-bottle with the metallic top and brush thereon, showing my improved attachment in proper relation to the bottle; Fig. 2, a plan view of said bottle with said cover and said brush removed, showing a top view of my attachment; and Fig. 3, an enlarged section on the line 3 3 of Fig. 2.

40 Like letters refer to like parts throughout the several views.

45 In the accompanying drawings, *a* denotes a mucilage-bottle of the most common form, and *b* a metallic lid having a central perforation therein adapted to receive and retain a brush, as *d*. These parts, as aforesaid, are of common construction and do not form an 50 essential element of my invention, as it is desired to produce an attachment which will accommodate itself to any form of bottle.

My improved mucilage-bottle attachment comprises a top rail *f*, preferably formed between the means for attaching it in position 55 in the form of a segment of an ellipse, as shown in Fig. 2. This rail *f* is preferably made integral with flaring extensions *g* *g*² *g*³ *g*⁴, which are provided with vertical extensions *h* *h*² *h*³ *h*⁴, preferably made integral 60 therewith.

Firmly attached to or made integral with said top are four prongs *k* *k*² *k*³ *k*⁴, which are adapted by contact with the interior of the neck of the bottle to secure my device firmly 65 in position.

In construction my device is preferably composed of one piece of metal formed in cross-section semicircular, as shown in Fig. 3, said device being preferably stamped out 70 of one integral piece of plate metal. It is to be observed, however, that it is not my intention to confine myself to this construction, as it is obvious that any desired construction, as of bent wire, may be employed without 75 departing from the spirit or scope of my invention. It is desirable, however, to have said upper rail present a smooth rounded surface, as this construction prevents the accumulation of mucilage thereon in any form 80 except of thin veneer.

The operation of my improved attachment is as follows: The cork of the mucilage-bottle having previously been removed the four prongs *k* *k*² *k*³ *k*⁴ are inserted in the neck of 85 the bottle, the extensions *g* *g*² *g*³ *g*⁴, resting on the exposed portion of the top thereof, preventing the escape of the attachment into the bottle. The top rail *f* is held out of contact with the interior of the neck of the bottle, as 90 it will be observed that only the outer periphery of the same could come in contact with it at any point and then only from an undue depression of the prongs *k* *k*² *k*³ *k*⁴. It will thus be observed that said top rail forms 95 an edge upon which to scrape the brush free from contact with the bottle, thus preserving a state of cleanliness in the same. If the mucilage should get upon the lower portion of the cover *b* of the bottle, the vertical extensions *h* *h*² *h*³ *h*⁴ by holding said top normally 100 out of contact with the neck of the bottle will also serve to aid in keeping said neck perfectly clear from the mucilage. The form of

the top rail *f* presents additional room and thus facilitates the introduction and removal of the brush.

The facility with which my attachment can be removed from the bottle and cleaned adds greatly to its effectiveness in operation and much to its practical value.

By the means above described I have fully attained the objects of my invention. I have 10 produced an attachment that is simple in construction, efficient in operation, and inexpensive to manufacture.

It is to be observed that it is not my intention to confine the invention to the exact construction and configuration herein shown and described, as it is clearly obvious that there may be many variations in minor details of construction without departing from the spirit of my invention.

20 Having fully described my invention, I claim as new and desire to secure by Letters Patent—

1. In a mucilage-bottle attachment, a top rail, downwardly-directed prongs whereby 25 said rail may be secured in the neck of a bottle and means whereby the escape of the attachment into the bottle is prevented, said prongs being so disposed as to hold said top rail out of contact with the neck of the bot-

tle, substantially as described.

2. In a mucilage-bottle attachment, a top

rail, flaring extension thereon whereby the escape of the attachment into the bottle is prevented and downwardly-directed prongs so disposed as to hold said top rail out of contact with the neck of the bottle, substantially as described. 35

3. In a mucilage-bottle attachment, a top rail, flaring extension thereon, whereby the escape of the attachment into the bottle is prevented, downwardly-directed prongs so disposed as to hold said top rail out of contact with the neck of the bottle and means whereby the cover of a bottle may be held out of contact with the neck, substantially as described. 40

4. In a mucilage-bottle attachment, a top rail, flaring extension thereon whereby the escape of the attachment into the bottle is prevented, downwardly-directed prongs so disposed as to hold said top rail out of contact 50 with the neck of the bottle and upwardly-directed extensions whereby the cover of a bottle may be held out of contact with the neck substantially as described.

In testimony that I claim the foregoing as 55 my invention I have signed my name, in presence of the subscribing witnesses, this 1st day of September, 1897.

MARK P. BRENNAN.
